UNITED STATES PATENT OFFICE.

RAYMOND H. STITES, OF ROCKFORD, ILLINOIS, ASSIGNOR TO TINY-TOTS FURNITURE CO., OF ROCKFORD, ILLINOIS, A FIRM COMPOSED OF CARL E. SWENSON, RAYMOND H. STITES, WALTER W. WICKHAM, AND FRANK I. LARSON, ALL OF ROCKFORD, ILLINOIS.

BABY-DRESSING CABINET.

Application filed May 1, 1923. Serial No. 635,940.

To all whom it may concern:

Be it known that I, RAYMOND H. STITES, a citizen of the United States, residing at Rockford, in the county of Winnebago and

- 5 State of Illinois, have invented certain new and useful Improvements in Baby-Dressing Cabinets, of which the following is a specification, reference being had to the accompanying drawings.
- 10 This invention relates to cabinets, and particularly to cabinets designed for use when bathing or dressing a baby.

The object of this invention is to provide a working table, as it were, which is particularly useful when the baby is being bathed or where its clothes are being changed and which is so constructed as to place within easy reach of the mother all of the necessary articles to perform the

20 work.

A further object is to provide a bathing cabinet of this character in which there is a canvas tray, which in its normal position extends over the bath tub or the space where- 25 in the tub is placed and upon which the baby may be laid when the baby is being dried or in changing its clothes, etc., this canvas tray, however, when it is turned up acting to prevent water from the bath tub 30 splashing against the wall and also acting to prevent the water from the bath tub from splashing against dry towels hanging upon the rack back of the tray.

A still further object in this connection is 35 to provide a canvas tray which is readily removable entirely from the frame of the structure so as to permit it to be readily cleaned.

Another object is to provide a device of 40 this character wherein the bath tub is readily removable after having been used and in which there is a front piece adapted to be turned up to simulate a drawer and extend across the space occupied by the bath

45 tub.

Still another object is to provide a device of this character which is very simple, effective and convenient for the purpose de- 50 scribed.

55 My invention is illustrated in the accompanying drawings, wherein:

Figure 1 is a perspective view of a bath tub constructed in accordance with my invention;

Figure 2 is a vertical sectional view there- 55 through with the member 27 raised;

Figure 3 is a perspective view of one of the drain board sections;

Figure 4 is a vertical sectional view showing the panel 34 raised and locked; 60

Figure 5 is a fragmentary perspective sectional view of the member 27 in its frame;

In these drawings, I have illustrated a cabinet of the character described which 65 consists, generally speaking, of a table having supporting legs, the table having its top formed with a substantially oval opening and means being disposed below this opening for supporting a bath tub in position. The back of the table or cabinet is extended upward to form a rack for the support of towels, etc., and above this rack there are one or more drawers designed to contain the articles necessary for dressing 70 the baby. A shelf at one side is hinged to the top and is adapted to be turned up into a horizontal position to support a wash basin or into a depending position.

In detail it will be seen that the cabi- 75 net consists of two forward legs 10 and two rear legs 11 and these rear legs 11 extend upward above the forward legs. The forward and rear legs are connected by the upper forwardly and rearwardly extending 80 rails 12 at the top of the legs and by the transversely extending braces 13. These braces 13 support a shelf 14 which is shown as narrower than the braces 13 but may be of any suitable size. 85 The legs 11 at their upper ends support a transverse shelf 15 and carried by said shelf and by the legs is a drawer casing 16 divided into two separate parts by a transverse partition and supporting two drawers 17. At- 90 tached to the legs 10 and 11 and extending rearwardly from the front legs at the upper ends thereof are the rails 18 having attached thereto the cleats 19.

The table top 20 is cut out at its center 100 so as to leave a rectangular opening, and fitting in this rectangular opening are the two splash drain sections 21. These are both alike. These sections are each made of a thin metallic sheet of enamelled metal, 105 the inner margin of each section being concavely curved and this inner margin is downwardly flanged, as at 22. The outer

margin of each section 21 is upwardly deflected so as to form a rim 23 extending horizontally outward. The table 20 is rabbed at 24 to receive this rim 23 so that 5 the sections 21 when in place in the table fit snugly to their seats and define an approximately elliptical opening immediately above the bath tub. These sections 21 may be removable but are preferably fixed and 10 when in place act to drain all the water downward into the bath tub which is disposed immediately below these sections.

The bath tub 25 has a rim 26 which is adapted to rest upon the cleat 19 so that 15 the bath tub may be entirely supported by these cleats 19. Adapted to be disposed over the enameled iron sections 21 and to fill the space defined by the rabbets 24 is a canvas tray 27. This tray is of heavy duck 20 or canvas stitched to a rectangular frame 28 of metal. This tray is not attached to the structure at all but merely rests within the space defined by the rabbet 24. When this tray is lowered so as to extend over 25 the splash drain sections 21 it forms a support for the baby in being washed or dressed, but when the child is being given its bath this tray is to be raised to the position shown in Figure 1 and, therefore, 30 acts to prevent water from splashing from the tub onto the wall or onto clean towels which may be hung upon the rod 29. The tray is held in its raised position by means of a catch. This catch consists of the base 35 or leaf 30 bifurcated at one end and rolled to form a bead and a detent 32 which is pivoted to this bead. The catch extends above its pivotal point, as at 33, and bears against the upper edge of the lower board 40 of the drawer casing 16. When the tray is turned up to an approximately vertical position, the upper margin of the tray will force the depending portion of the catch 32 inward to allow the tray to pass and 45 then when the tray is released the weight of the upper portion of the tray will force the depending portion outward and the upper portion of the catch will bear against the lower board of the drawer casing 16 and the tray will be held from falling downward until intentionally released.

It is desirable to provide means for concealing the space within which the bath tub is placed so that this space will look like 55 a drawer, and to this end I provide a panel 34 which has a knob upon its front face 38 and is designed to simulate a drawer front, this being swingingly supported from the plates 18 or inside rails by means of supporting hangers 35. Each of these hangers 60 is formed of strap iron and is angularly bent at one end, this end being fastened by screws to the inner face of the panel. The opposite end of the iron 35 is pivoted 65 to the member 18. The inner face of this

panel carries the cross pieces or cleats 36 and the block 37. It is to be understood, however, that this panel does not support the tub but that the tub is entirely supported by its flange and that there is a 70 clearance between the panel and the bottom of the tub. When the tub 25 is in place or removed, the panel may be turned up into its vertical position and will bear against the ends of the inside rail 18, and 75 this panel is held in this position by means of a latching device, as illustrated in Figure 4, which comprises a keeper 38 mounted in a recess on the under face of the table top, this keeper extending inward and upward at an angle. On the inside face of the panel 34 there is attached a spring leaf 39, the upper end of which is outwardly and downwardly curved so as to engage over the keeper. To this spring leaf is attached a push button 40 which extends outward through an opening in the panel 34. When this panel is closed and it is desired to open the panel, it is only necessary to push in on the push button 40 and this 80 will shift the upper end of the spring leaf 39 inward, detaching its hooked end from the keeper 38, whereupon the panel may be lowered. When the panel is raised, however, the spring leaf will spring back so as to pass the keeper and will then spring into engagement with the keeper in an obvious manner.

Hinged to one end of the table top 20 is a shelf 41, this shelf being so hinged 90 that it may drop down to a vertical position and acting to support this shelf is a sectional brace 42 composed of the two sections which are pivoted to each other, this brace being so constructed that when the table top is turned to a horizontal position the sections of the brace cannot break at the joint but will hold the table top supported. The details of this brace form the subject-matter of another application filed 105 of even date herewith and it is not believed necessary, therefore, to particularly describe the brace.

Detachably engaged with the side edge of the shelf 41 is a soap dish 43. The soap tray is made removable principally to facilitate cleaning. When the shelf is dropped, the soap dish hangs vertical with the shelf, though, of course, the soap must be removed before dropping the shelf. The rod 29 is designed to support towels, wash cloths, etc., and obviously when the tray 27 is turned up to the position shown in Figure 1 it will protect the dry towels 115 from being splashed as well as protect the wall from being splashed. In order that the tray may be readily lifted, a small tab is sewed to the margin of the tray on its upper face. A lower towel rack 29^a is preferably disposed between the legs 10. 120 125 130

It will be seen that a device of this kind is very convenient and that after the child has outgrown its use it is only necessary to provide a top which will extend over the 5 table top 20 in order to convert the structure into a dressing table or wash basin stand. It will be seen that the stand is thoroughly substantial and sanitary. The tub is adapted to be entirely removed and 10 not merely drained, as is the case with other devices of this character known to me. The canvas tray, because of the fact that it can be removed, may be kept entirely clean and sanitary. Inasmuch as the canvas tray is 15 disposed over an opening in the table top, the canvas or duck will yield slightly when the baby is laid thereon so as to form a comfortable support for the baby. This canvas tray is made from soft white double 20 filled duck, and inasmuch as the tray is entirely removable from the cabinet it is obvious that the tray may be turned over if desired and one side used for the purpose of supporting the baby when being dried or 25 when its clothes are being changed and then this stained side of the tray may be turned downward and the clean side of the tray turned upward. The cabinet is to be of such height that the table will be convenient 30 for the mother in washing the child.

I claim:-

1. In an article of furniture of the character described, a table top having a rectangular opening, the margin of the opening 35 upon the upper face of the top being rabbeted, a thin metallic members disposed to fit in the rabbeted table top and formed to define an elliptical opening, means for supporting a bath tub below this metallic member, a tray consisting of a rectangular frame, a textile webbing fastened to the frame, the tray being adapted to be disposed within the rabbeted upper face of the table top and extend over the metallic member and the bath tub, and means 45 for supporting the tray in an approximately vertical position.

2. An article of furniture of the character described comprising a table top formed with a rectangular opening and having four legs, two of the legs at the rear of the table top extending upward above the table top and supporting a drawer casing, drawers within the casing, a sectional 50 drain board of thin metal supported within the rabbet of the table top and cut away to define when in place an elliptical opening, means disposed below the table top for supporting a bath tub beneath the elliptical opening in the drain board sections, a tray formed of a rectangular frame, a canvas webbing attached to the frame, the tray being adapted to fit within the rabbeted portion of the top or to be raised to an 55 approximately vertical position, and means

upon the drawer casing for supporting the tray in this vertical position.

3. An article of furniture of the character described comprising a table top formed with a rectangular opening and having four legs, two of the legs at the rear of the table top extending upward above the table top and supporting a drawer casing, drawers within the casing, a sectional drain board of thin metal supported within the rabbet of the table top and cut away to define when in place an elliptical opening, means disposed below the table top for supporting a bath tub beneath the elliptical opening in the drain board sections, 70 a tray formed of a rectangular frame, a canvas webbing attached to the frame, the tray being adapted to fit within the rabbeted portion of the top or to be raised to an approximately vertical position, and means upon the drawer casing for supporting the tray in this vertical position, said means consisting of a pivoted catch movable freely in one direction to permit the tray 75 to pass the catch but held from movement 80 in the opposite direction.

4. An article of furniture of the character described comprising a table top having a rectangular opening, a thin metallic member disposed to rest on the table top 95 and having an elliptical opening therein, means for supporting a bath tub below this metallic member, a tray consisting of a rectangular frame, a webbing fastened to the frame, the tray being adapted to be disposed upon and extend over the metallic member and the bath tub, and means for supporting the tray in an approximately vertical position on the table top at the rear of the metallic member.

5. An article of furniture of the character described comprising a table top having an opening, legs supporting the table top, rails attached to the legs at opposite ends of the table and below the table top, a bath tub having a rim adapted to be engaged with said rails, and hangers pivoted to the rails and a panel attached to said hangers and adapted to be shifted into position to extend across the front of the article between said legs to thereby conceal the space immediately beneath the table top or be shifted into a horizontal position beneath the bath tub.

6. An article of furniture of the character described comprising a table top having four legs attached thereto, two of the legs at the rear of the table top extending above the table top, a drawer frame supported upon the upper ends of said legs, the table top being rectangular in form and having a rabbeted margin, a drain board formed in two thin metallic sections, the margins of the sections being deflected to fit said rabbet and the sections when in 120 125 130

place defining an elliptical opening, a tray consisting of a rectangular metallic frame, a canvas webbing attached to the frame, the tray being adapted to be turned down into said rabbet of the top and extend over said drain board sections or turned upward with its upper edge immediately beneath the drawer frame, a catch on the drawer frame adapted to support the tray

in its vertical position, means disposed below the table top for supporting a bath tub beneath the opening in the drain board sections, and a panel adapted to be turned up in front of said space and latched to the table top. ¹⁰

In testimony whereof I hereunto affix my signature.

RAYMOND H. STITES.
